UNITED STATES PATENT OFFICE.

NORMAN C. BASSETT, OF LYNN, MASSACHUSETTS, ASSIGNOR TO THE THOMSON-HOUSTON ELECTRIC COMPANY, OF CONNECTICUT.

TROLLEY FOR ELECTRIC RAILWAYS.

SPECIFICATION forming part of Letters Patent No. 508,669, dated November 14, 1893.

Application filed July 18, 1892. Serial No. 440,301. (No model.)

To all whom it may concern:

Be it known that I, NORMAN C. BASSETT, a citizen of the United States, residing at Lynn, county of Essex, State of Massachusetts, have 5 invented a certain new and useful Improvement in Contact-Trolleys for Electric Railways, of which the following is a specification.

My invention relates to what are known as "drop trolleys" for electric railway cars, and 10 its object is to improve the construction and operation of these devices.

Drop trolleys are used to prevent injury to the overhead conductors and stay wires when the trolley wheel jumps off the wire. They 15 are arranged to automatically relieve the tension of the springs by which the trolley wheel is kept pressed up against the conductor. This permits the trolley pole to fall low enough to avoid hitting the conductor or stay wires.

20 The invention consists in a catch for locking the pole in the lowest position to which it may fall when released from the action of the springs, thus preventing it from rebounding.

25 The invention further consists in a device for nullifying the automatic action of the "drop" mechanism, so that the parts may act like an ordinary trolley.

The invention also consists in an improved 30 device for fastening the trolley pole into the socket.

The invention also consists in an improved bearing for the spring support frame giving greater ease of movement and permitting the height of the frame to be reduced.

35 In the drawings, Figure 1 is a side elevation showing the parts in working position. Fig. 2 shows the springs thrown out of action and the pole locked with the trolley wheel out of contact with the conductor. Fig. 3 is a sectional view showing the mechanism transformed into a plain trolley. Fig. 4 is a section of the ball bearing for the spring support frame, and Fig. 5, is a section of the pole clamp, on line 5-5, Fig. 3. Fig. 6 is a top 40 plan view of the drop trolley mechanism.

45 The pole socket piece A is provided with trunnions a by which it is hinged on a horizontal axis to the frame B, which consists preferably to two side pieces extending horizontally from a plate C. The socket piece 50 carries a segment ratchet a' concentric with

the trunnions a , and at the rear upper end of the ratchet are two laterally projecting studs a^2 .

Pivoted on a transverse axis b at the front 55 end of the frame B, are one or more toggle levers D, rigidly united by cross bars d when more than one is used, and connected at their outer ends to the springs E, which in turn are attached to the studs a^2 on the socket 60 piece. The inner ends of the toggle levers are pivoted to two links F, the rear ends of which contain slots f , through which pass the studs a^2 .

When the parts are brought into the position in which they are shown in Fig. 1, the line along which the springs exert their force lies above the axis b , so that the front ends of the links are held down against the sides of the frame as shown. The pole is free to 70 vibrate as usual, without disturbing the position of these parts. But should the trolley wheel jump off the wire, the pole is pulled up, and the studs a^2 strike the front ends of the slots f , jarring the links upward, and permitting the springs to trip the toggle levers into the position shown in Fig. 2, thus relieving the tension of the springs and permitting the pole to fall, so as to prevent it from striking the overhead wires. In order to lock the pole 80 in this position, so that it cannot rebound, or sway up and down, a pawl G is pivoted on a transverse axis between the sides of the frame adapted to engage with the ratchet a' and prevent upward movement of the pole, though 85 not interfering with the downward movement thereof. The pawl is normally held out of engagement with the ratchet by an arm d' projecting from the toggle levers D and bearing upon the tail g of the pawl. When the 90 springs are released, however, and the toggle levers turn up the arm is lifted off the tail of the pawl, permitting it to fall upon the ratchet. To re-set the springs, the pole is drawn down to a horizontal position, or as far as it will go, 95 the studs a^2 pulling back the links F and straightening out the toggle joint formed by the links and the levers D, until the front bar d rises above the pivot b , when the toggle joint becomes locked, as in Fig. 1, and the pole is 100 lifted by the springs against the conductor.

To provide for nullifying the operation of

the drop mechanism, should it be desired or necessary to do so, a lock is arranged to hold the toggle set, under all conditions. This may be preferably a hook H, pivoted on the same 5 pin as the pawl G, and adapted to catch over the rear bar d of the toggle lever D. When not in use, the hook is turned back upon the pawl G.

It has been customary to drill a hole in the 10 socket piece for the butt of the trolley pole, and to turn the pole to fit, clamping it by set screws. But when the end of the pole becomes battered it is difficult to get it either in or out, and it frequently becomes loose. To overcome 15 these objections, the socket piece A has a recess cored in it, and the pole I is held therein by a clamping plate A' and suitable bolts a³. This saves all finishing of the socket or pole, the only machine work necessary being to drill the holes for the bolts. The clamp enables the poles to be readily inserted or removed, and also accommodates poles of different sizes.

Instead of swiveling the spring support 20 25 a standard as heretofore, a ball bearing is used, which is preferably constructed as follows: To the car is fastened a stand K, having three feet k and a low cylindrical flange k' in which is a groove, preferably external. The stand also has a contact bar k² for the attachment of the connecting wires. The 30 spring support has a cylindrical shell c which fits easily over the flange of the stand K, a clearance of about one sixteenth of an inch 35 being allowed between them. The shell has an annular groove, preferably internal, which is arranged to correspond with the groove in the flange, the two forming an annular bearing for the balls L, which are introduced 40 through a hole in the shell. A plug M closes the hole, and prevents the balls from being displaced or accidentally lost. The plug, however, is not necessary to the operation of the device, since there is no tendency to force 45 the balls out of the bearing. It will be noticed that the balls sustain all the pressure, both vertical and horizontal and serve to unite the stand and the spring support. The balls

are well protected from dust, and require little or no oil. The trolley turns so easily on these bearings that it follows the wire with surprising tenacity, and is far less liable to jump off than the ordinary trolley. The bearing is low, so that the height of the frame is several inches less than the ordinary style. 55

What I claim as new, and desire to secure by Letters Patent, is—

1. The combination with a drop trolley having a pivoted pole-socket piece, provided with a ratchet, of a pawl adapted to engage with 60 said ratchet to lock the trolley-pole in its depressed position, substantially as described.

2. The combination, with a pivoted trolley having tension springs attached to a toggle lever, of a pawl to engage with the pole-socket 65 piece when the toggle is tripped and the pole drops, and an arm on the toggle lever to normally hold the pawl out of engagement, substantially as described.

3. The combination, with a drop trolley, of a lock for nullifying the operation of the drop mechanism, substantially as described. 70

4. The combination, with a drop trolley comprising a toggle lever, of a catch for preventing the tripping of said toggle lever, substantially as described. 75

5. The combination, with a drop trolley comprising a toggle lever, of a hook for engaging with one end of said toggle lever, to prevent it from being tripped, substantially 80 as described.

6. A trolley-pole socket piece containing a recess, in combination with a clamping plate and suitable bolts, for holding the butt of the pole, substantially as described. 85

7. A trolley-pole support containing a semi-circular recess to receive the butt of the pole, in combination with a clamping plate and suitable bolts, substantially as described.

In witness whereof I have hereunto set my hand this 15th day of July, 1892.

NORMAN C. BASSETT.
